UNITED STATES PATENT OFFICE.

FRANK WEISENBERG, OF NEW YORK, N. Y.

RECEPTACLE.

No. 900,901.

Specification of Letters Patent.

Patented Oct. 13, 1908.

Application filed March 6, 1908. Serial No. 419,430.

To all whom it may concern:

Be it known that I, FRANK WEISENBERG, a citizen of the United States, and a resident of the city of New York, borough of Brooklyn, 5 in the county of Kings and State of New York, have invented a new and useful form of Receptacle, of which the following is a specification.

My invention relates particularly to the 10 construction of a receptacle from which a milk or cream bottle can be removed only upon the opening of the receptacle by the person for whom the milk or cream is intended. Such a device is of especial value 15 where full bottles are delivered at a time when there is no one to receive them, in which instance it is the custom to deposit the bottles outside of the house door with the consequent danger of loss through theft, 20 or through the dishonesty of the delivery agent who may fail to deliver bottles when it is his duty so to do. By the use of my device failure to deliver bottles is shown by the 25 empty condition of the receptacle or receptacles and after insertion, which may be made by any one, the bottles cannot be removed by any unauthorized person.

I do not wish to be understood as limiting myself to the particular construction of my 30 invention shown in the drawings herewith and hereafter described, since such a construction may be capable of various modifications as desired, without departing from the spirit of my invention which consists in 35 the construction, arrangement, and combination of parts set forth in and falling within the scope of the claims hereto appended.

Like characters of reference denote like 40 parts in all the figures of the drawings. Figure 1 represents a view in side elevation of my receptacle, in position for use; Fig. 2 represents a sectional view in front elevation of my receptacle; Fig. 3 represents a detail view in top elevation of the retaining members of my receptacle; Fig. 4 represents a detail view in side elevation, partly in section, 45 of the top of my receptacle and hanger members.

The construction of my invention is as fol- 50 lows:

The receptacle A comprises a body member a, preferably cylindrical in form, open at both top and bottom, and of a size sufficient to permit of the insertion therein of the bot- 55 tle or other package in connection with which it is to be used. A top member b is

adapted to be inserted in and close member a. The top member is provided with a handle 2, and bottom member a is provided with a hanger member 1 which is pivotally fastened 60 on the outside thereof at points X and is adapted to be swung up over the top member b when the latter is in place, the top of the hanger member 1 then being over and adjacent to the handle 2. The hanger member 1 65 and handle 2 are provided with horizontal slots 3 and 4 respectively, which register when the parts are assembled as described.

An angle bracket member 5, adapted to be attached to the wall or door casing, is provided at its lower end with upwardly extending lip 7, and at its upper end with a second lip 8. To the outside of bottom member a is secured a holder member 6 adapted for the insertion of lip 7; lip 8 is adapted to be inserted in the registered slots 3 and 4 and is provided with an aperture 9 in the portion projecting above such slots. A lock 10 of desired form may be inserted in aperture 9, thus securing the assembled receptacle from 80 being removed from the bracket 5 without first removing the lock 10.

Inside the top member b, adjacent the bottom thereof are secured spring retaining members 11, which in the form shown project upwardly and inwardly to form an opening of the desired shape smaller in size than the interior of the receptacle or of the article to be inserted therein. The spring-retaining members may be fastened to the inside of the 85 member b in any desired manner, such as being soldered directly thereto, or by being held between the inner wall of the member and a collar member secured thereto.

The bottom member a is made of such a 90 length that the article to be inserted in the receptacle A will not protrude from the bottom thereof when secured in position.

The operation of my invention is as follows: The bracket 5 is secured to the wall or 100 door casing in any desired location by the use of screws or other fastenings, the use of screws being permitted since they cannot be removed when the receptacle is in place. The top member b is then inserted in the top 105 of the body member a, the hanger member 1 of the body member being swung up over the top so that the aperture 3 therein registers with the aperture 4 in the handle of the top member b; the assembled receptacle is then 110 engaged with the bracket 5 by simultaneously inserting the lip 7 from below in the

holder member 6 on the outside of the bottom member *a*, and inserting the lip 8 from underneath in the registered apertures 3 and 4 in the hanger member 1 of the bottom member *a* and in the handle 2 of the top member *b* respectively; the lock 10 is then fastened through the aperture 9 in the top of the lip 8 and the receptacle is ready for the insertion of a bottle *B*. The delivery agent 10 inserts a bottle in the receptacle by pressing it up therein from the bottom until the lip 12 of the bottle neck passes beyond the retaining members 11; the bottle can not then be withdrawn from below since it cannot be 15 grasped because of the inclosing receptacle member *A*; hence the bottle will remain in the receptacle until the lock is removed, the lips 7 and 8 disengaged and the top and bottom members *a* and *b* separated, whereupon 20 the bottle may be easily disengaged from the retaining members.

It will thus be seen that my device is a protection against theft as has been stated, simple in design and construction, durable, may 25 be operated with ease, and manufactured at a low cost. Protection is also furnished against dirt, moisture, and heat or cold. The construction may be such that a plurality of bottles can be inserted in one receptacle, and receptacles may be adapted for use 30 with bottles of various sizes. The retaining member may be of any suitable design and secured in position in any desired manner, while the locking means at the top of the receptacle may be a combination or any other 35 well known form of lock. It will also be apparent that the form of my device may be adapted for use with any form of bottle, can, or other package, it not being essential that 40 there be a projection such as a bottle lip which is forced through the retaining members, since a package with a plain surface may be inserted and held between said members, the receptacle being made of sufficient 45 length to prevent interference with the inserted package.

Having thus fully described my invention, what I claim as new and desire to secure by Letters Patent is:

50 1. In a device of the class described, a holder open at one end thereof, spring retaining means adapted to receive an article inserted in said open end, said means being adapted to permit of the removal of the inserted article only in the direction of its insertion and said holder being adapted to prevent the removal of the article after insertion.

60 2. In a device of the class described, a holder open at one end and provided with a cover for the opposite end, means adapted to receive an article inserted in the open end of the holder, said means being adapted to permit of the removal of the inserted article only 65 in the direction of its insertion, and said

holder being adapted to prevent the removal of the inserted article in the direction of its insertion.

3. In a device of the class described, an open ended holder provided with a cover 70 adapted to close one end, said holder being adapted to receive an article inserted in an open end thereof and to retain said article against removal while the cover is in position.

4. In a device of the class described, a holder comprising a casing open at one end and provided with a cover adapted to close the opposite end, and means carried by the cover adapted to receive an article inserted 80 in the open end of said casing, said holder being adapted to prevent the removal of the inserted article while said cover is in position.

5. In a device of the class described, a 85 holder comprising an open ended casing provided with a cover adapted to close one end, and means carried by the cover adapted to receive an article inserted in the open end of the casing, said holder being adapted to prevent the removal of the inserted article while the cover is in position and said receiving means being adapted to hold the inserted article to effect its removal with the removal of the cover.

6. In a device of the class described, a holder provided with an opening for the insertion of an article, and means adapted to retain an inserted article, said holder being adapted to prevent the removal of the article 100 from the retaining means before the article has been partially removed from the holder.

7. In a device of the class described, a holder open at one end and provided with a cover adapted to close the opposite end, means adapted to receive an article inserted in the open end of the holder, said holder being adapted to prevent the removal of the inserted article from the receiving means in the direction of its insertion, before the article 110 has been removed from the holder.

8. In a device of the class described, a casing open at one end, spring retaining means within the casing adapted to receive an article inserted in the open end and to permit 115 of the removal of the article only in the direction of its insertion, said casing being adapted to prevent the removal of the article from the open end after insertion.

9. In a device of the class described, a holder comprising a casing open at one end and a cover adapted to close the opposite end, spring retaining means within the holder adapted to receive an article inserted in the open end of the casing, said casing being adapted to prevent the removal of the inserted article from the open end while the cover is in position.

10. In a device of the class described, a holder comprising a casing open at one end 130

and a cover adapted to close the opposite end, spring retaining means within the holder adapted to receive an article inserted in the open end of the casing, said casing being adapted to prevent the removal of the inserted article from the open end while the cover is in position and said retaining means being adapted to permit of the removal of the inserted article after the cover has been 10 removed.

11. A device of the class described comprising a body member, an end member adapted to close one end of said body member, a hanger member secured to said body 15 member and adapted to be brought in position over said end member, means for securing said hanger member in position over said end member, and means adapted to hold an article inserted in said body member.

12. The combination with a support of a casing open at one end connected thereto, a cover adapted to close the opposite end of the casing, and means preventing the removal of the cover while the casing is in position on said support.

13. The combination with a support formed

with an upright flange of an open ended holder provided with an end member adapted to close one end of the holder, a handle on the end member, an aperture in said handle adapted to permit of the insertion of said flange therein, a hanger member carried by the holder, an aperture in said hanger member adapted to permit of the insertion of said flange therein, and means adapted to hold an 30 article inserted in the holder.

14. In a device of the class described, an open ended holder, an end member adapted to close one of the ends of the holder, means for securing the end member in position, said 40 means comprising a hanger member carried by the holder and adapted to be brought in position over the end member, and means adapted to hold an article inserted in the holder.

45 In testimony whereof I have hereunto signed my name in the presence of two subscribing witnesses.

FRANK WEISENBERG.
